UNITED STATES PATENT OFFICE.

JOHN SIGWALT, JR., OF CHICAGO, ILLINOIS.

PRINTING-STAMP.

SPECIFICATION forming part of Letters Patent No. 399,089, dated March 5, 1889.

Application filed September 25, 1886. Serial No. 214,514. (No model.).

To all whom it may concern:

Be it known that I, JOHN SIGWALT, Jr., of Chicago, county of Cook, State of Illinois, have invented certain new and useful Improvements in Printing-Stamp, of which the following is hereby declared to be a full, clear, and exact description, sufficient to enable others skilled in the art to make and use the same.

10 The invention relates to printing-stamps wherein the ink-pad is located in near relation to the printing-bed, so that the stamp may be alternately inked and brought into position for printing, as desired.

15 The invention relates more especially to that class of stamps in which the die-plate frame is positively retained within limits, so as to be held in fixed relation after each shift above the printing-bed or ink-pad, as the case 20 may be, and the improvements in construction are designed to secure, primarily, the same movement back and forth in the use of the stamp as is usual in the ordinary stamp carried freely in the hand of the operator 25 and caused to descend by him upon the pad and printing-bed alternately.

A further object of the invention is to secure the accurate vertical movement of the stamp after each shift, so that it shall meet 30 the pad or the bed squarely and evenly.

These objects of invention are accomplished by the improvements in construction set forth in the accompanying specification, and pointed out in the claims at the conclusion 35 thereof.

Figure 1 is a view in perspective, and Fig. 2 a view in longitudinal section, of a printing-stamp embodying my improvements.

Mounted in near relation to the printing 40 bed or surface A are the upright standards B, which, for convenience, may be formed at the ends of and in piece with the box or case retaining the ink-pad C. The bottom of the box or case is raised above the face of the 45 printing-bed, so that in printing a long strip the same may be fed or drawn freely past and beneath the bottom of the pad-case to receive the successive impressions without being impeded by such case or box.

50 Pivoted to the standards B are the swinging arms D, which at their opposite ends are

journaled to the die-plate frame E, which latter is thus retained between the said swinging arms and may be carried back and forth thereby in position above the ink-pad 55 and the printing-bed, respectively. The die-plate frame E is provided with the usual socket or bearing to receive the reaction-spring and the vertical plunger F, which carries at its lower end the die-plate G. A guide 60 or pin, g, projecting from the die-plate passes through an eye, d, of the frame and serves to align the die-plate during its vertical descent. To better insure this desired position of the die-plate, there are provided near each end of 65 the die-plate frame E suitable rests or seats, e, located on each side of the swivel-connection between the swinging arms D and the die-plate frame. These seats e contact with stops or rests 1 1 and 2 2, located on the 70 standards B, in position above the ink-pad and the printing-bed, respectively. Owing to the location of such stops and rests, a firm even bearing is afforded for the die-plate frame at the end of its alternating shift, in 75 position over the ink-pad or printing-bed, as the case may be, so that a square vertical stroke of the die-plate against the ink-pad or the surface being printed may thereby be certainly insured.

It is manifest that the construction of the rests or stops may be varied, if desired, and that either set of the rests 1 1 or 2 2 may be omitted, although in practice the employment 80 of both sets thereof is preferred.

For convenience there may be shifting guides 3 3, secured to the printing-bed A, to govern the position of the separate sheets as the same are presented beneath the die-plate 85 for printing.

I am well aware that printing-stamps have been heretofore constructed in which a die-plate was mounted between vertically-swinging arms, said plate being pivotally connected with said arms in such manner as to permit 95 it to be pressed successively against the ink-pad and the object to be printed; and I am also aware that printing-stamps have been heretofore constructed in which the die-plate was carried upon the end of a plunger mounted 100 upon a horizontally-swinging arm, whereby the die-plate could be brought successively

over the inking-pad and printing-surface. In the first of these constructions, in which the die-plate was pivotally connected to the vertically-swinging arms, the die-plate was not 5 carried by a vertical plunger susceptible of movement independent of the swinging arms, and no provision was made whereby the movement of the swinging arms could be arrested before the vertical downward movement of 10 the die-plate was completed. With the printing-stamps in which the die-plate was carried by a plunger mounted upon the end of a horizontally-swinging arm the inking of the die-plate and the printing operation could be 15 properly effected; but this arrangement of the die-plate upon a horizontally-swinging arm necessitated both a lateral and vertical movement of the operator's hand at each operation of inking and printing. By my present 20 improved construction I attain all the advantages of the back-and-forth movement incident to stamps the die-plates of which are mounted upon vertically-swinging arms, and I also avoid the danger of uneven inking and 25 printing heretofore encountered in this class of stamps by providing means whereby the movement of the vertically-swinging arms shall be arrested before the die-plate can strike the ink-pad or printing-surface and 30 by mounting the die-plate in a suitable frame, so that its further movement after the swinging arms are arrested will be necessary before

the type-face of the die-plate can be thrust against the inking-pad or object to be printed.

Having thus described the invention, what I claim as new, and desire to secure by Letters Patent, is—

1. In a printing-stamp, the combination, with the die-plate, the vertical plunger carrying said die-plate, and the die-plate frame 40 wherein said plunger is held in a manner free to move, of vertically-swinging arms whereby said die-plate frame is carried, standards in pivotal connection with the vertically-swinging arms, and stops or rests for sustaining the 45 die-plate frame during the vertical downward movement of the plunger, substantially as described.

2. In a printing-stamp, the combination, with the die-plate and the vertical plunger, 50 of the pivoted die-plate frame E, having rests or seats e at each side of its pivotal points, the standards provided with stops whereon said seats will bear, and vertically-swinging arms pivotally connected to the die-plate frame and the standards, whereby during the vertical movement of the plunger the pivoted die-plate frame will be guarded against movement about its pivot-bearings and in downward direction, substantially as described.
